UNITED STATES PATENT OFFICE.

ELISHA S. SNYDER, OF SNYDER'S MILLS, WEST VIRGINIA.

HARVESTER GUARD-FINGER.

SPECIFICATION forming part of Letters Patent No. 241,436, dated May 10, 1881.

Application filed March 11, 1881. (No model.)

To all whom it may concern:

Be it known that I, ELISHA S. SNYDER, a citizen of the United States, residing at Snyder's Mills, in the county of Jefferson and State 5 of West Virginia, have invented a new and useful Improvement in Harvester Guard-Fingers, of which the following is a full, clear, and exact description, reference being had to the accompanying drawings, forming part of this 10 specification.

My invention relates to guard-fingers for reapers and mowers, and has for its object a saving of time usually required for grinding sickles.

15 My invention consists in a sectional guard-finger constructed with two reversible plates, each having two cutting-edges, the said plates being arranged to engage with the sickle-knives, and held in position by a removable 20 top section, also provided with beveled edges, which may be utilized by inserting a sickle having inverted knives, as will be hereinafter more fully described.

In the accompanying drawings, Figure 1 is 25 a plan view with the top section removed; Fig. 2, a side view, partly in section; Fig. 3, a cross-view, partly sectional; Fig. 4, a perspective view of one of the plates, and Fig. 5 a view of front end of top section.

30 A represents a guard-finger for a harvester, having a removable top section, a, which encloses the upper surface of the sickle-knives. Arranged underneath said section, and held down in position by the same, are a pair of 35 two-edged plates, b b, which have their rear ends dovetailed between a small central lug, c, and two broader side projections, c', and their forward ends embedded in rectangular recesses d in the said finger, so that by lifting 40 the forward ends up the plates may be easily withdrawn, inverted, and returned to position.

The plates b are made tapering, to correspond 45 with the shape of the finger, and each has its two cutting-edges beveled upon opposite sides, so that either cutting-edge, no matter which side of the plate is uppermost, shall be adjacent to the cutting edge of the sickle. It will 50 be seen, therefore, that the plates are not reversible from side to side, but simply invertible upon one side each, which is the only method by which four available cutting-edges could be provided.

The rear ends of said plates, upon each edge, 55 are provided with two oppositely-beveled recesses, b' b'', one in front of the other, so that

when the plate lies upon either side the hindmost bevel on the inner edge and the foremost bevel on the outer edge shall dovetail between the central lug, c, and either side projection, c'. The said cutting-edges are to be 60 ground, and when the harvester is in use, to avoid the loss of time by grinding sickles, the said plates need only to be inverted, to do which requires only the removal of screw e, which holds down the top section, a. This 65 section is provided with lugs or stationary pins a' on its under surface, which fit into recesses in the finger and keep it from turning upon the screw. It is further provided with a bevel, a², and recess a³ on its forward end, 70 which engage with a beveled lug, a⁴, and pin a⁵ on the upper end of the finger, whereby it is kept from either vertical or lateral movement. The edges of this top section, which are adjacent to the sickle-knives, are beveled 75 on the upper side, so as to form cutting-edges, which may be utilized by inserting a sickle having its knives inverted, by which additional cutting-edges are provided, and contact of the sickle with sand and earth is avoided. 80

In this manner, by having two sickles only, one with inverted knives, a harvester may be run two or three times as long between the grinding of sickles as could be done without such a device; besides, there need be no delay 85 for that purpose during the hours devoted to labor.

I am aware that a harvester guard-finger having a removable top plate has before been used. I therefore do not claim such a feature, 90 broadly; but

What I claim as new, and desire to secure by Letters Patent, is—

1. A guard-finger provided with a pair of two-edged invertible plates and a removable 95 upper plate having beveled edges, said parts being constructed and arranged substantially as shown and described, and for the purpose set forth.

2. In a guard-finger, a pair of invertible 100 plates, b, having their cutting-edges beveled upon opposite sides, and provided at their rear ends with two oppositely-beveled recesses, b' b'', in combination with central lug, c, and side projections, c', substantially as shown and described. 105
